UNITED STATES PATENT OFFICE.

LEONARD J. HURDMAN, OF DETROIT, MICHIGAN, ASSIGNOR OF ONE-HALF TO LEON L. OVENSHIRE, OF DETROIT, MICHIGAN.

DESIGN FOR A REFUSE OR WATER RECEPTACLE.

Application filed July 26, 1922. Serial No. 3,208. Term of patent 3½ years.

To all whom it may concern:

Be it known that I, LEONARD J. HURDMAN, a citizen of the United States, residing at the city of Detroit, county of Wayne, State of Michigan, have invented a new, original, and ornamental Design for Refuse or Water Receptacle, of which the following is a specification, reference being had to the accompanying drawing, forming a part thereof.

Figure 1 is a perspective view of the receptacle looking toward one corner thereof, and

Fig. 2 is a similar view looking toward the opposite corner of the receptacle, showing my new design.

I claim:

The ornamental design for a refuse or water receptacle, as shown.

LEONARD J. HURDMAN.
